UNITED STATES PATENT OFFICE.

THALES LINDSLEY, OF NEW YORK, N. Y.

IMPROVEMENT IN BRICK-KILNS.

Specification forming part of Letters Patent No. 121,179, dated November 21, 1871.

To all whom it may concern:

Be it known that I, THALES LINDSLEY, have invented a new and Improved Kiln and Apparatus for Water-Smoking, Burning, and Cooling Bricks, Tiles, &c.; and I declare the following to be a clear, full, and concise description of same, such as will enable others skilled in the art to which it pertains to make and use the same, reference being had to the accompanying drawing forming part of this specification.

Its offices are to provide: First, facilities for readily handling the bricks, tiles, &c., from the time they are formed until ready to remove after burning, and facilities for removing same. This is effected by means of peculiar brick-cars and a railroad or roads composed of removable rails. Second, doors being necessary to admit of charging and discharging the kiln and ingress and egress of cars and trucks, to provide practically air-tight and steam-tight doors for these openings. Third, that the doors aforesaid may swing freely and clearly, and not be interrupted nor pierced by the rails of the track, (when in drying or discharging it may become necessary to have them frequently opened and closed,) to provide a track draw-bridge which, when the door is opened, can be lowered so that the ends of the track may fall within the door and join onto the ends of the main track, and when the car has passed out, be raised again and the door closed. Fourth, facilities for reversing the draught in any part of the kiln, and for changing the order of operation in either water-smoking, burning, or cooling, from the top downward or from the bottom upward, at will. This is effected by the peculiar system of vertical and horizontal flues, for transmission of hot and cold air, and by the opening of certain ports and closing of others, and by dampers. Fifth, to the utilizing of the heat given off from a burning-chamber. This is effected by my peculiar combination of the chambers and flues.

In the drawing, Sheet I is a ground plan of the kiln provided with eight chambers, B C D E F G H K, and the general drying-chamber A A. In the construction of the floors of a chamber here represented, B B show the upper floor composed of rectangular tiles *a*, pierced with holes for influx or efflux of hot or cold air. These tiles rest upon stringers, shown in *c c*, which in turn rest on the lower solid floor of rectangular

tiles *d d*, which rest on the sleepers *e e*, which finally rest on the foundation floor of non-conducting material. These floors and stringers are shown in longitudinal section at lower right-hand corner, and in cross-section at lower left-hand corner. It will be seen that, besides the passages left between the stringers and sleepers, they are themselves pierced with semi-cylindrical openings, to admit of the perfectly free diffusion of hot air in burning or of cold air in cooling. Where continuous flues pass immediately under the lower floor, and between the sleepers, as represented at *b b b* in *e e*, and in cross-section at lower left-hand corner, they are made of tile and packed with non-conducting material. *r* is a system of railways for charging and discharging. *e* are cold-air openings, and *e¹* are cold-air flues; *b b*, horizontal hot-air flues; *b¹*, vertical hot-air flues, communicating, also, with system of diffusing flues under the top floor. *b² b²* are the fire-flues; *h²*, the ash-pits; *h*, the corner; *h¹*, the lateral, and *h³*, the fuel-bin buttresses.

Sheet II shows a section, vertical, on C D of Sheet I, showing how the middle division of the triple walls, of which this kiln is constructed throughout, is provided with cold-air flues *e¹ e² e³*. *x* are openings through the inner division of a wall to a chamber, into the compartments beneath the first floor. *x³* is similar opening into body of chamber. *e¹* are vertical hot-air flues, which, communicating with *e²*, *e³*, and *e⁴*, carry hot air from a burning-chamber and discharge same into the drying-chamber A A through openings shown in Sheet 5, at *h* and *x¹*; or, if desired, can be discharged through the chimney-flue *x⁴* into the chimney. In the drawing of brick-car, at upper left corner, the leaves are hinged at one end, resting on a shelf at the other end. The drawing shows its construction clearly. In upper right-hand corner is a car, arranged with shelves, *q*, which shelves are divided (as shown in the plan of a shelf below) into two parts, this division being along the curved line *a a*, each leaf turning or revolving laterally around the stay-rod *q²*, shown in the vertical and horizontal elevation and plan, respectively. When the leaves swing in together they unite along the line *a a* and form a continuous shelf.

Sheet III shows a section on line A B of Sheet I, and also sections along H I and L M of this

sectional drawing A B. In A B, *g* is the cycloidal fuel-bin incorporated in a buttress. The furnace *o* is on the same sectional cycloidal curve of the fuel-bin. *f* is the fire-flue. *i* is the opening to the hot-air descending flue, shown in section LM above. *V* is a damper, operated by a rod, *V*¹, through a close-fitting cap, *V*², which damper can be lowered, as will be seen by the drawing, to a position such as will cut off the direct entrance into the chamber C of the heat from the furnace and oblige it to pass through *i* down *b*³, through opening *b*² into *b*; thence (Sheet 2) into *e*¹—supposing the openings *e* to be closed—and through *e*², *e*³, *c*², *c*³, and *c*⁴, and finally through openings *x*¹ and *k* into the drying-chamber. Or the damper may be lowered as before, and the tumbler-valve *c*, shown at the right of section A B, to be turned over to the right so as to close the passage *b*²; then the draught would pass from openings *e* (in Sheet 2) through cold-air flues *e*¹ into *b*, (Sheet 3;) through opening *b*² into *b*³; up *b*³ through *i* into fire-flue *f*; thence through the grate-bars, carrying the hot products of combustion, through *b*¹ into the intercommunicating flues under the upper floor; thence through the openings in the tile flooring; and thus to burn the bricks from the bottom upward. The heat would then, in escaping, pass up through *x*³, through *x*¹, into the drying-chamber. The traction-truck, shown at the upper left-hand corner of this sheet, is for use in pushing against a car or train of cars in the drying-chamber, attaching itself to such car by the latch *l*, in the usual manner, and fully indicated by its construction here shown. A rope or chain is then attached to the ring *l*¹, and the cars are then drawn out by means of capstan or similar appliance, and the direction of the power is changed so as to correspond to the direction of the track by interposed pulley-wheels, upon which the rope or chain bears at the angles of the track's course.

Sheet 4 shows a side elevation of the kiln, in which A A shows the entrance to the drying-chamber, and *z*⁵ are the door-frames, upon which the doors (at upper left corner) are hung. The doors and the frames are made with corresponding lateral and vertical slots and ribs, the object being to have them close into each other, so that, when the door is closed, it will be nearly steam or air-tight. In order that these grooves and ribs may be made, of course the door must lap broadly onto the frame at bottom, top, and sides. The door may be made in plane form, or it may be made so as to set well in, having its top, bottom, and sides set at an angle as represented, fitting against corresponding angular surfaces of the frame. The latter would form the closest-fitting door. At the upper right hand is a track draw-bridge, composed of track *w*², lever *w*⁴, rollers *w*, and chains *w*¹. The construction is evident. By pulling the lever to the right the part *w*² is raised, and the door into which it was extended can be closed. It extends far enough within the door to attach onto the end of the track inside the drying-chamber. The roller *w*³

is provided with cams, into which the lever is inserted.

Sheet 5 shows the general arrangement of the chambers with respect to each other, and the course of the system of hot-air horizontal flues; showing the disposition of the openings (into the different chambers) *x*¹, *x*², *x*³, &c., and the points at which vertical hot-air flues *c*², *c*¹, *c*⁵, &c., enter this system of horizontal flues.

Sheet 6 is a plan of the top of the kiln, showing air-ports *s*¹ *s*¹, used to introduce cold air in cooling; vent-ports *p*¹ to each burning-chamber for ingress of cold or egress of hot air; eye-ports *p* *p* piercing the domes; dampers *s* *s*, located in all the horizontal flues, for regulating the amount and direction of draught; other dampers, *s*² and *s*³, for changing the point of efflux of heat or of admitting cold air; dampers *k* *k* *k*¹ for regulating influx of hot air to drying-chamber, smoke-stack, flues, and man-hole, *j*¹ *j*² *x*⁶, respectively.

The operation of this kiln will be evident to any one skilled in the art, hence needs no further description. Its novelties are also clearly expressed in the drawing and claims.

I do not intend to claim the pulleys and the capstan when used in this connection, as suggested.

What I claim as new, and desire to secure by Letters Patent of the United States, is—

1. The drying-chambers A A and burning-chambers B, C, D, &c., when placed in juxtaposition and otherwise constructed and arranged, as shown and described.

2. The doors and door-frames to a drying-chamber, provided with ribs and grooves, substantially as and for the purposes set forth.

3. The track draw-bridge with lever *w*⁴, ways *w*², rollers *w*, cam-roller *w*³, and band or chain *w*¹, in connection with the doors and removable rails, all substantially as and for the purposes described.

4. In combination with a burning-chamber, the furnace *o* with flue-damper *v*, furnace-door *g*¹, and the tumbler-valve *c*, constructed and operating substantially as described.

5. The combined buttress and cycloidal fuel-bin, the latter being provided with throat-feeding damper, all constructed and operating as indicated.

6. The combination and arrangement, herein shown, of the fire-chamber, dampers *v*, and co-operating flues, for the purpose set forth.

7. The brick car, shown at A, Sheet 2, provided with shelves divided into two wings, each wing revolving laterally upon vertical stay-rods.

8. In the kiln described, the combination of devices and appliances, as set forth.

9. The traction-truck with curved handle *l*¹, wheels *w*, and arms *l* provided with beveled hooks *l*¹, constructed as shown, and for the purposes set forth.

THALES LINDSLEY.
